UNITED STATES PATENT OFFICE

RICHARD M. WATSON, OF DETROIT, MICHIGAN

BASE MEMBER FOR LOOSE LEAF BINDERS

Application filed November 11, 1927. Serial No. 232,493.

This invention relates to a base member for loose leaf binders, and has to do particularly with the provision of novel and inexpensive paper retaining members and connecting means therefor.

Loose leaf binders of the prior art may be divided into two general classes, first, those provided with paper retaining rings formed of round wire and round connecting means, 20 and second, those formed with round or oval wire inserts and plate connecting means. The latter form has heretofore been the more desirable on account of the thin plate connecting members and flexibility of movement. However, this latter form has been 15 much more expensive both as to materials required and the cost of assembly.

It is the object of the present invention to provide paper retaining and connecting means therefor which embodies all the advantages of the prior art binders having plate connecting means and which is much cheaper to manufacture and much more simple and compact and more permanent in construction, there being only three pieces in its construction as compared to seven and eight pieces in the plate type heretofore used.

The present invention does away with the separate plate and ring inserts of the prior art and provides in place thereof an extremely simple and inexpensive one-piece plate and insert, the rings of the one-piece member being oval in cross section and the connecting means between the rings being flat so as to permit of a relatively thin shell structure. More specifically, this novel paper retaining means and connecting means therefor is formed of a single piece of plain wire, the ends of which are turned up and shaped to form the retaining rings, and such rings being stamped oval in cross section, and the wire between the rings being shaped to present two high spots and being stamped in the form of a thin, flat plate or strip of stock. Not only is this novel paper receiving and supporting means formed in one piece, but the connecting strip or stock between the paper retaining ends thereof is so shaped as to give a very quick "snap-over" action to open

and close the spring members and also to operate with relatively small friction.

Another feature of the present invention has to do with the formation of a one-piece shell structure which extends substantially 55 the full length of the cover, and which presents a relatively flat construction due to novel securing means for securing the one-piece shell structure to the back of the cover, said securing means being entirely hidden by 60 the one-piece shell structure.

In the drawings:

Fig. 1 is a perspective view of a binder equipped with my novel base member and illustrating particularly the relatively flat 65 shell structure for permitting the leaves of paper to lie flat on the cover.

Fig. 2 is an enlarged sectional view taken on line 2-2 of Fig. 1 and showing the stamped members for connecting the ring 70 members.

Fig. 3 is a detail perspective view of a one-piece paper receiving and supporting means.

Fig. 4 is a bottom plan view of my assembled base structure and showing the lug members 75 for securing the base to the binder.

Fig. 5 is a detail perspective view of one of the lugs for securing the shell and the assembled structure to the back of the cover.

Fig. 6 is a detail perspective view of one 80 end of my preferred shell structure.

Fig. 7 is a bottom plan view similar to Fig. 4 and showing the structure before it is assembled on the back of the cover.

Figs. 8, 9 and 10 illustrate the various steps 85 in the formation of my one-piece paper receiving and supporting means.

Fig. 11 is a detail view, partially diagrammatic, of a die structure for fabricating the ends of the wire members for forming the 90 paper receiving rings.

Fig. 12 is a diagrammatic detail view illustrating one manner of forming the oval portion of the paper receiving members prior to forming the same by the die shown in Fig. 11. 95

While my invention resides in an extremely simple, compact and neat appearing base member as a whole, it may best be described by referring to the most important part which makes possible this compact assembly. This 100

member is best illustrated in Fig. 3 and may be generally designated 1, and consists of two semi-circular end members 2 and 3 which are preferably oval in cross section, and a connecting member which is flattened out from a piece of round wire to substantially rectangular shape, as best shown in Figs. 2 and 10.

This connecting member is preferably pre-formed while still a round wire so as to present two contacting points 4 and 5 on one side, and three contacting points 6, 7 and 8 on the other side. The high points or contacting points 4 and 5 are provided with oppositely struck out members 9 and 10. This entire member, as shown in Fig. 3, is formed of a single piece in a novel manner as will be later described.

The member 1 forms both a right and left hand member, and the ends of the semi-circular members 2 and 3 are merely formed with V shaped joints which may be termed universal V shaped joints, as the one member 2 is provided with a projecting V joint 11, and the other member 3 is provided with a recessed V joint 12. The member 1, as well as the joints 11 and 12, make it a universal member as, regardless which member is picked up, it will form either a right or left hand member and the joints will always fit. In ordinary construction now on the market the oval ring member inserts are formed with joints of complicated manufacture so as to make them universal, as otherwise, it would be necessary for the person assembling the member to pick out the correct ring insert at each point of assembly.

While my novel hook carrying toggle plate may be utilized in practically any type of shell member, I have shown a shell member and means for securing the same to the back of the binder which is peculiarly adapted and cooperates with my novel paper receiving and supporting member. This shell member may be generally designated 13. It is manufactured by taking a piece of strip stock, preferably the length of the back of the cover, and suitable apertures 14 punched therein and spaced a suitable distance apart according to the punching in the sheets of paper. The flat connecting portions of two members 1, as shown in Fig. 3, may then be inserted in the shell structure with the semi-circular parts 2 and 3 extending through the apertures 14, as shown in Fig. 2. The edges 15 and 16 of the shell 13 are then bent over, as shown in Figs. 2, 4 and 7, whereby the portions 4 and 5 of each member 1 contact and are held in contacting relation by the oppositely struck out portions 9 and 10. It will be seen that the edges 15 and 16 may be bent over much sharper and much flatter than where the connecting shaft for the ring members is a round wire, thus providing a general base member which is relatively thin. The oval members

2 and 3 will fit the apertures 14 nicely and serve to position the members 1, as shown in Figs. 4 and 7. The lugs 9 and 10, being oppositely struck out, will cooperate with each other to hold the flattened portions of each ring supporting member in operating relation. The central part of the shell member is preferably given a very slight curvature, as shown in Fig. 2, but this curvature is much flatter than that necessary to be given where plain wire shafts or connecting members are used, as the space movement of the flat members 1 is necessarily much less than when the plain round wire members are used. It further will be obvious that as the flat members 1 are moved back and forth they will move over a center line at which point they are compressed against each other by reason of being held in the channels formed by the turned over edges 15 and 16. This provides for a "snap-over" movement on opening and closing of the rings.

The ends of the shell member 13 are turned down, as at 17 to provide for a neat appearance, and the side walls of the ends of the shell member are substantially perpendicular to the back of the shell, as shown at 18 and 19 in Fig. 6. As a securing means, I have provided a suitable retaining member or lug 20, as shown in Fig. 5, which is provided with a suitable aperture 21 for receiving the rivet. The ends of the lug 20 are preferably turned down, as at 22, and are provided with extending portions 23 which fit in the grooves formed by the turned over edges 15 and 16. It will be obvious that the width of the turned down members 22 is approximately the width of the shell at the points 18 and 19, and that the lugs may thus be inserted at the ends of the shell member and be connected to the ends of the shell member by relative movement between the two so that a portion of the lug 20 extends within the turned over edges 15 and 16.

In the preferred use of this shell structure the base member is assembled, as shown in Fig. 7, and two lugs 20 are riveted in place on the back of the cover, with the ends 22 extending upwardly, as shown in Fig. 5. The complete shell structure, as shown in Fig. 7, may be then secured thereto by placing one end of the shell over one of the lugs 20, moving it relative to the lug until the other lug member comes within the opening at the other end of the shell, and the shell member moved back into central position and both lug members thus partially engage the turned down edges 15 and 16 of the shell, as shown in Fig. 4. These flat lug members 20 thus cooperate with the flattened paper retaining and supporting members 1 to permit of a relatively flat base member 13. It will be obvious that other types of shell structure may be utilized, such as that disclosed in my copending application #204,736, filed July 18, 1929.

- 11, 1927, but the shell structure shown herein is the preferred form as it cooperates with the paper retaining member to permit of a much flatter or thinner shell structure as a whole.
- 5 It will be seen that the shell member shown herein, extends practically the full length of the binder and completely covers up all interior movable parts and rivets so as to present a very neat and attractive appearance.
- 10 The apertures 14 are on the side of the shell member so that the shell member really presents an imperforate upper surface extending practically the full length of the binder.
- The one-piece paper receiving and supporting member 1 is preferably fabricated by first taking a predetermined single length of cheap round wire and bending up the ends thereof the proper length to provide the semi-circular hook members, as shown in Fig. 8. At the same time the connecting portion 25 of this wire is preferably shaped or distorted, as shown in Figs. 3, 4 and 7. The next step is to place the bent up portions 2 and 3 of the wire in suitable dies such as shown in Fig. 5, 20 to give the same a substantially oval shape. These stamped ends 2 and 3 may then be placed in suitable dies such as shown in Fig. 11 where these end portions are given a ring form or, as shown in Fig. 2, are given substantially a semi-circular shape. The die is so shaped, as shown in Fig. 11, that the ends of the members 2 and 3 are cut simultaneously with the shaping of the oval part of the wire so as to form the V shaped joint in the ends 30 of the wire, one die member forming an externally extending V, as at 11, in Fig. 3, and the other die member forming an internally extending V, as at 12. The portion of the member 1, as shown in Fig. 2, extending between the oval rings 2 and 3, may then be placed in a suitable die whereby to flatten out the member between the ring members 2 and 3, and also to strike out oppositely positioned lugs 9 and 10 on the high points 4 and 5. It 40 will be obvious that these lugs will be struck out simultaneously with the flattening of the connecting member.
- It will thus be seen that I have provided a novel ring construction or hook carrying toggle plate which is formed of a single length of wire, and which member has oval paper receiving means and a flattened portion between said rings whereby to permit of a relatively thin base or shell construction.
- 50 55 The oval retaining rings present a very neat appearance, and the flat connecting member not only permits use of a flatter shell member but also insures a more positive and quicker snap-over action in each direction.
- 60 It will furthermore be obvious that I have provided in combination with a novel one-piece ring and wire construction, a novel shell structure which is relatively thin and extends only a short distance above the back of the binder whereby the paper held in the retain-

ing members is positioned relatively flat or approximately parallel with each cover of the binder. This prevents creasing of the paper at the edge of the shell structure, and also in combination of the oval wire prevents tearing of the holes in the paper. It will be further more obvious that my novel shell structure extends approximately the entire length of the cover and completely covers up all rivets and other parts of the base member so as to present a neat and attractive appearance.

Another very important feature which will be obvious from this disclosure is the providing of a one-piece paper receiving and supporting member, all parts of which are so formed as to make the member universally adaptable as either a right or left hand member. This includes not only the flat connecting member, but also the oval rings and the simple V-shaped joints at the ends of the ring members. Thus not only is the member very inexpensive to manufacture but its very construction makes it very easy and positive to assemble and requires the use of only a single set of dies.

Claims:

1. A hook carrying toggle plate for loose leaf binders, comprising a single length of wire having its ends bent to form spaced retaining hooks, substantially oval in cross section and having the portion between the retaining means flattened.
2. A hook carrying toggle plate for loose leaf binders, comprising a single length of wire having its ends bent to form spaced retaining hooks, the portion of the wire between the retaining rings being flattened and substantially rectangular in cross section.
3. A hook carrying toggle plate for loose leaf binders, comprising ring members supported by a flat connecting member, said connecting member being permanently bent transversely of its length at a plurality of points.
4. A base member for a loose leaf binder, comprising in combination an apertured shell member having its longitudinal edges bent inwardly, and oppositely disposed paper receiving and supporting means each consisting of ring members extending through said apertures, and flattened out connecting members, said flattened out connecting members being transversely bent whereby to present one or more contacting surfaces with each other at their inner sides, and one or more contacting surfaces positioned in said grooves formed in the inwardly bent edges of the shell.
5. A hook carrying toggle plate for loose leaf binders having a retaining shell, comprising a single member having its ends turned to form paper retaining means, the connecting portion between the hooks being relatively wide and thin and bent transversely of its length to form two contacting por-

tions on its inner edge, and a plurality of spaced contacting portions on its outer edge for contacting with the binder shell.

6. A hook carrying toggle plate for loose leaf binders having a retaining shell, comprising a single length of wire having its ends shaped to form paper retaining hooks substantially oval in cross section, the connecting portion between the hooks being relatively thin and substantially rectangular in cross section, said connecting portion being transversely distorted to present a plurality of alternately spaced contacting portions on its inner and outer edges, the contacting portions on the other edge cooperating with the binder shell.

7. A loose leaf binder, comprising in combination a cover including a back, a shell member formed of a single flat piece of metal extending substantially the length of a cover, the upper surface of said shell being imperforate except for openings formed therein for receiving paper-retaining rings, the paper-retaining rings being positioned in said openings and having connecting members formed of stock relatively flat in cross section to permit of a relatively thin shell member, and a plurality of lugs adapted to be secured to the back of the cover and connected to the ends of the shell at the underside thereof to secure the shell member to the back of the binder.

8. A loose leaf binder, comprising in combination a cover, a one piece shell member extending approximately the length of the cover, openings in said shell member, connected ring members of a paper retaining and supporting means extending through said openings, the connecting portion between said ring members being relatively flat, the shell member having turned over edges for directly receiving the edges of said flat portions between the ring members, and a relatively small lug member adapted to be secured to the back of the cover and connected to said shell member by said turned over edges.

9. A loose leaf binder, comprising in combination a cover, a one piece shell member extending approximately the length of the cover, paper retaining and supporting means positioned within said shell member, said means being provided with ring members extending above the shell member and with flat blades for connecting the ring members, said flat blades being oppositely positioned and maintained in operating relation by narrow longitudinal edges of said shell member turned over upon the blade member, and a lug member adapted to be secured to the back of the cover and connected to the underside of said shell member by turned over edges of said shell member.

In testimony whereof I affix my signature.
